UNITED STATES PATENT OFFICE

2,379,661

HIGH-PRESSURE STEAM GENERATOR

Leslie E. Sebald, Ridgewood, N. J., assignor to The Griscom-Russell Company, New York, N. Y., a corporation of Delaware

Application June 7, 1939, Serial No. 277,788

5 Claims. (CL. 122—32)

This invention relates to high pressure steam generators indirectly heated by a circulating medium of hot fluid. The objects of the invention are to provide a durable, efficient boiler in which all possibility of cross-leaks between the heating and heated fluids is eliminated, in which the occurrence and repair of leaks in the separate circulating systems will be substantially minimized, in which extreme temperatures and pressure may be safely used without danger and without subjecting the structure to the stresses of differential expansion. Important additional objects are to provide an evaporator structure readily adaptable to varying conditions, particularly in the temperature of the heating fluid and the amount of heat to be extracted therefrom.

Broadly, I attain these objects by employing wholly independent circulating systems for the heating and heated fluids and by effecting the necessary transfer of heat from one to the other solely by metallic conduction without at any point enclosing one circulating vessel within the other.

Specifically, I have solved these problems in a particularly effective embodiment of my invention, by employing the heat exchanging units disclosed in Letters Patent No. 2,013,187, granted September 3, 1935, to Price. The use of this device as an element of a steam generator in the combination hereinafter described and claimed permits the solution not only of the difficulties inherent in all previous indirectly heated boilers of which I am aware, but also of certain difficulties inherent in water tube boilers generally.

In the accompanying drawings I have shown a preferred embodiment of my invention designed primarily as a waste heat boiler and temperature regulator for the hot fluid salt used as the heat absorbing medium for exothermic catalytic reactions. Other embodiments of my invention employing means for attaining its objects as broadly herebefore suggested may be used without departing from the scope and spirit thereof.

Fig. 1 is a transverse vertical section through a steam generator embodying my invention, taken on the line 1—1 of Fig. 2;

Fig. 2 is a side elevation of a steam generator embodying my invention;

Fig. 3 is a longitudinal vertical section of a steam generator embodying my invention;

Fig. 4 is a transverse vertical section of my invention showing the generator installed in a supporting and insulating tower;

Fig. 5 is a horizontal section taken through line 5—5 of Fig. 4;

Fig. 6 is a transverse vertical section of the upper and lower headers of the heat exchanging portions of the generator installed in a supporting tower;

Fig. 7 is a longitudinal vertical section of the upper and lower headers of the heat exchanging portions of the generator installed in a supporting tower;

Fig. 8 is a horizontal section taken on the line 8—8 of Fig. 6;

Fig. 9 is a schematic diagram showing a system of circulation of the heating and heated fluids;

Fig. 10 is a schematic diagram showing a modified system of circulation; and

Fig. 11 is a schematic diagram showing another modified system of circulation.

In this embodiment of my invention the heating fluid is introduced by the inlet manifold 1 and flows through the six inlet connecting pipes 2 into the lower headers 3 of the heat exchanging units 4, up through the upper headers 5, around the return bends 6, down again through the heat exchanging units 4 and incoming connection pipes 7, across the clean-out header 8 into the outgoing connecting pipes 7 up through the opposite heat exchanging units 4, around a second return bend 6, down again through the opposite heat exchanging units 4 and outlet connecting pipes 2 out the outlet manifold 12. The heated fluid, in this instance water, is fed through the steam drum 13 and maintained at a level indicated by the water line shown in Figs. 1 and 3. This fluid passes through the downcomers 14 into the mud drum 15 and thence out by the paired upcomer pipes 16 into the opposite heat exchanging units 4. It is there flashed into steam and discharged through the paired connecting pipes 17 into the steam drum 18 behind the baffles 18.

The heat exchanging units 4 embodying the invention of the Price patent hereinbefore mentioned, as clearly shown in Fig. 5 and, in somewhat more detail, in Fig. 8, consist of two heating tubes 25 and two heated tubes 26 nested together by and expanded into the close packed perforated metal member 20. These members serve to conduct the heat from the tubes containing the heating fluid to the tubes containing the heated fluid, and to reinforce the tubes greatly against extreme pressures. It will be particularly observed that by use of this construction all possibility of cross-leaks between circulating systems is avoided, that no glands or stuffing-boxes are required, and that no problems of differential expansion arise in the heat exchanging portions of

this boiler. All the tubes connecting the drums and manifolds with the heat exchanging portions of this generator have wide compensation bends 9 so that any differential expansion between the drum and manifold supports and the connecting tubes is amply taken care of. The circulation of heating and heated fluids provided in this embodiment of my invention is straight-line, inherently free from bubbles and dead pockets, resulting in uniform heat transfer throughout the evaporating portion of the system.

The steam drum of this generator is provided with the usual boiler accessories, e. g., feed-water regulator, gauge glass connections, safety valve and clean-out connections, feed-water circulator and heater, and other appurtenances not a part of this invention. Similarly the heating fluid circulating system is provided with clean-out plates and positive circulator means not a part of this invention.

A vertical steam generator of the type illustrated is preferably supported by an insulated tower 23 of structural steel as shown in Figs. 4 and 5. At the lower part of the framework 24 of the tower 23, the salt manifolds 1, 8 and 12, and the mud drum 15 are rigidly attached. The lower headers 3 of the heat exchanging units 4 are supported by and between blocks 11 attached to the vertical tower members 36.

The heat exchanging units 4, comprising two heating tubes 26 and two heated tubes 25 structurally united by closely packed metal members 20, act as supporting columns to maintain the weight of the steam drum 13, its various attachments and its insulation 22. This whole steam drum assembly is rigidly attached to the upper platform 21. This platform 21, in turn, is supported by the blocks 35 attached to it and resting on the upper headers 5 of the heat exchanging units 4. When the whole unit is at atmospheric temperature not in operation, this platform 21 does not bear on the tower frame 24, but is vertically clear therefrom and is maintained in its proper position horizontally by the guide members 30 thereof.

Thus the platform 21 constitutes a floating frame supported by the heat exchanging units 4, but guided in its vertical movements by the tower structure 24, bearing with it the steam drum 13 and insulating cap 22. This whole assembly is free to rise and fall with variations in temperature, particularly in any starting and stopping of operations, according to the expansion and contraction of the heat exchanging units 4. The compensation bends 10 in the downcomers 14 relieve any stress of differential expansion therein.

The use of the manifolds 1, 8, and 12 in the heating circuit, of the steam and mud drums 13 and 15, and particularly of the feed water distributor 33 inside the steam drum 13 maintains a substantial uniformity of temperature between the various heat exchanging units 4. Thus all parts of this device are protected from the strains of differential expansion by my invention, and in particular the difficulties of sealing tubing in its passage through the walls of a jacket are avoided.

Figs. 6 and 7 show details of construction in headers 3 and 5 of the heat exchanging units 4. At the upper headers 5 the salt pipes 25 within the heat-exchanging units are connected by the return bend 6, which is removably held in place by the clamp yoke 27. At the lower headers 3 the pipes 25 are connected with the salt inlet,

outlet, and clean-out headers as hereinbefore described by connecting pipes 2 and 7, and are expanded into the header 3 in grooved holes. These holes, extending through the header 3, are tapped on opposite sides thereof by the pipes 2 and 7, and are sealed at their lower ends by the plugs 29 removably held in place by the clamp yoke 28. By removing the return bend 6 and plugs 29 the salt tubes 25 are opened up for easy cleanout.

At the upper headers 5, the water tubes 26, expanded into grooves in the header, extend through it to a welded connection with the steam drum connecting tubes 17. At the lower headers 3 the water tubes 26, expanded into grooves in the header, extend through it to a welded connection with the mud drum connecting tubes 16.

Essentially, the headers 3 and 5 are specialized thick members permitting the hereinbefore indicated attachments and connections, but also serving as heat conducting means exactly as do the thinner closely packed members 20 in which the tubes 25 and 26 are also expanded as shown in Fig. 8.

In Fig. 9 is shown schematically the circulating system of the heating fluid which I have already described in connection with the embodiment of my invention selected for the purpose of illustration in Figs. 1-8. In it the hot circulating fluid must pass four times in the heating tubes 31 and 32 in paths parallel to the steaming tubes 26 in its passage from the intake manifold 1 to the outlet manifold 12. This circulating system I have termed the "series system." Without making any alteration in the heated circulation and with only simple alterations in the heating structure the modified circulating systems shown in Figs. 10 and 11 may be achieved.

In Fig. 10 I show a schematic heating fluid circulating system which I have termed "series-parallel." In it the hot circulating fluid must pass twice in the heating tubes 31 and 32 in paths parallel to the steaming tubes 26 in its passage from the intake manifold 1 to the outlet manifold 12. As can be readily understood, this change is accomplished by connecting the inlet header 1 with the heating fluid upcomers 31 in both opposed banks of heat exchanging units, by connecting the outlet header 12 by means of the return bends 6 to the heating fluid downcomers 32, and omitting entirely the intermediate cleanout manifold 8.

In Fig. 11 I show a schematic heating fluid circulating system which I have termed "parallel." In it the hot circulating fluid must pass once in the heating tubes 25 in a path parallel to the steaming tubes 26 in its passage from the intake manifold 1 to the outlet manifold 12. In this arrangement I omit the return bends 6 and elevate the inlet manifold 1 above the opposed banks of heat exchanging units. I connect all the salt pipes 25 to this manifold at their top and to the outlet manifold 12 at the bottom. This construction is possible with slight alteration in the structure—i. e., so placing the compensation bends 10 of the water downcomers 14 as to leave place for the elevated inlet manifold 1, removing the return bends 6, and making the connections described, omitting, of course, the cleanout manifold 8.

Thus, my invention permits of standardization in manufacture, while providing great adaptability to various requirements of flow velocity and temperature drop on the heating side in individ-

ual installations. This flexibility provided by my invention permits a high salvage value of a generator constructed according to my invention in the event that a user dismantles any particular installation of it.

Water tube boilers, whether heated by flue gases or by other circulating hot fluids, e. g. mercury vapor, in shells or jackets, present several problems which are solved by my invention. The source of these problems is lack of uniformity of flow of the heating fluid past the water tubes. This results in inequality of heat transfer in the various tubes, often in serious hot and cold spots, with attendant strain and inefficiency. The prior art is crowded with attempts to solve this problem, chiefly by baffles designed in various ways to equalize the flow. This solution of the problem introduces its own difficulty—the bubbles and congestions attendant on changes of flow direction.

My invention, by use of straight-line positive circulation insures absolute uniformity of flow readily adjustable as to rate to insure the optimum heat transfer in each installation. The use of the device of the Price patent is a particularly happy solution of this problem, but the scope of my invention is not limited to such use.

The embodiment of my invention hereinbefore described has been selected for illustration because it shows my solution of the problems stated in a form I deem preferable, and is not intended as a limitation of my invention. It is obvious that without departing from the spirit or scope of my invention other specific forms of indirect steam generators employing wholly independent circulating systems for the vaporizing and vaporized fluids, effecting the necessary heat transfer by metallic conduction without any point enclosing one circulating vessel within the other, may be constructed. For example, horizontal or inclined instead of vertical water tubes might be employed, or heating and heated circuits not flowing in parallel, but in divergent paths substituted.

I claim:

1. A water tube boiler heated by a hot fluid circulating medium comprising a steam drum, a mud drum, downcomer tubes descending from said steam drum to said mud drum, steaming tubes rising from said mud drum to said steam drum, a heating medium intake manifold, a heating medium outlet manifold, tubes for circulating the heating medium from said intake manifold to said outlet manifold, and metal members structurally connecting said heating tubes with said steaming tubes for a portion of their respective lengths and transferring heat from said heating tubes to said steaming tubes, said downcomer tubes, heating tubes, and steaming tubes being separately provided with means for relieving expansion stresses therein.

2. A vertical water tube boiler heated by a hot fluid circulating medium comprising a heating medium intake manifold, return bends, heating medium tubes rising thereto from said intake manifold, a cleanout manifold, heating medium tubes descending thereto from said return bends, additional return bends, heating medium tubes rising thereto from said cleanout manifold, a heating medium outlet manifold, heating medium tubes descending thereto from said additional return bends, a mud drum, a steam drum, steaming tubes rising from said mud drum to said steam drum, a multiplicity of metal heat conducting members having four parallel perfora-

tions in each member, the heating medium tubes rising to and descending from each return bend being paired and nested with and structurally connected to a pair of said steaming tubes for a portion of their respective lengths by passing through the four perforations of a plurality of said metal heat conducting members, said heating medium tubes and steaming tubes when nested being parallel and vertical, and downcomer tubes descending from said steam drum to said mud drum, all the aforementioned tubes being separately provided with expansion bends and all of the aforementioned tubes, drums, or manifolds being wholly external to any other of said tubes, drums or manifolds.

3. In a water tube boiler according to claim 1, a supporting structure comprising a framework, the mud drum, intake and outlet manifolds being attached thereto and the lower ends of the structurally connected portions of the heating and steaming tubes abutting thereon, and a platform, the steam drum being attached thereto, said platform abutting on the upper ends of said structurally connected portions of the heating and steaming tubes and being mounted on said framework slideable in the direction of the expansion of said portions of the heating and steaming tubes.

4. In a water tube boiler according to claim 1, a supporting structure comprising a framework extending to the tops of the structurally connected portions of the heating and steaming tubes, a boiler insulating shell co-extensive therewith and mounted thereon, the mud drum, intake and outlet manifolds being attached to and the lower ends of the aforementioned portions of the heating and steaming tubes abutting on said framework, a platform, the steam drum being attached thereto, said platform abutting on the aforementioned portions of the heating and steaming tubes and being mounted on said framework slideable in the direction of the expansion of said portions of the heating and steaming tubes, and a boiler insulating cap mounted on and extending below said platform, overlapping the aforementioned insulating shell in closely spaced relation to the outside surface thereof to a greater distance than the maximum expansion of the aforementioned structurally connected portion of the heating and steaming tubes.

5. In a water tube boiler heated by a hot fluid circulating medium, vertical water tubes, a drum being connected to the tops thereof for collecting the steam therefrom and means for supplying water thereto being connected to the bottoms thereof, independent vertical tubes for circulating the heating medium, said tubes for circulating the heating medium and said water tubes being mutually wholly external, metal heat conducting means structurally connecting said tubes for circulating the heating medium with said water tubes for the major portion of their respective lengths, and a supporting means comprising foundation structure for supporting the parts of said boiler below the structurally connected portions of said water tubes and said tubes for circulating the heating medium, a tower structure, and a floating structure for supporting the parts of said boiler above said structurally connected portions, said floating structure resting on said structurally connected portions and mounted on said tower structure slideable in the direction of the expansion of said tubes.
